UNITED STATES PATENT OFFICE.

HUGO M. VOWINKEL, OF SHEBOYGAN FALLS, WISCONSIN.

REGISTER.

Application filed April 30, 1928. Serial No. 274,101.

This invention relates to registers and is particularly directed to a hot air register.

Objects of this invention are to provide a novel form of register which is so made that it is provided with an additional grating which normally hangs downwardly and is superimposed on the ordinary grating, so that the register normally has the appearance of the ordinary register, but which is adapted to be swung upwardly about its upper edge and hooked in a horizontal position by means of retaining latches, so that the auxiliary grating is adapted to hold articles to be dried, or otherwise treated, with the warm air.

Further objects are to provide a device which is adapted to hold the articles in the position where they are in contact with the greatest quantity of flowing air passing from the register, and to provide a device which is automatically held in closed position by the tendency of the latches to swing downwardly into vertical position, whereby rattling or other evidences of a loose connection are wholly avoided when the device is closed.

An embodiment of the invention is shown in the accompanying drawings in which:

Figure 1 is a vertical sectional view taken on the line 1—1 of Figure 2, showing the auxiliary grating elevated;

Figure 2 is a face view of the structure shown in Figure 1 with parts broken away.

Referring to the drawings, it will be seen that the usual register body 1 has been illustrated as provided with the usual grating 2. The auxiliary grating 3 is a duplicate of the usual grating 1 and is hinged as indicated at 4 at its upper horizontal edge. The auxiliary grating is provided with inturned ears 5 which pivotally receive the latches 6. These latches are each provided with notches 7 adjacent their innermost ends. Normally, the auxiliary grating 3 hangs down over the grating 2 and completely covers it and thus the register presents all the appearance of the usual type of register. However, when it is desired to use the device for holding articles, the auxiliary grating is swung outwardly about its upper edge into the horizontal position shown in Figure 1. The latches 6 receive a portion of the usual grating in the notches 7 and thus hold the auxil-

iary grating rigidly in its horizontal position.

When the grating is not in use, the latches 55 are detached and the grating swings downwardly. When the parts are in their normal position, the latches 6 hang downwardly and thus bear against the transverse members of the usual grating 2 and thereby lock the 60 auxiliary grating tightly against the main grating and prevent rattling or inadvertent dislodgment.

It will be seen further that the device may be very cheaply constructed, that it is 65 eminently practical, and that it holds the articles to be dried in the position where they receive the maximum flow of heated air.

It is to be noted particularly that by having the auxiliary grating hinged adjacent its 70 top that when it is swung outwardly into a horizontal position, that it is thereby located in a place to receive the maximum amount of heated air. It is well known that the heated air from the registers rises and consequently by hinging the auxiliary grating in the position described, that the maximum benefit from the heated air is secured.

Although the invention has been described in considerable detail, such description is 80 intended as illustrative rather than limiting as the invention may be variously embodied and as the scope of such invention is to be determined as claimed.

I claim:

1. A register comprising a body portion having a main grating, an auxiliary grating adapted to normally lie upon said main grating, said auxiliary grating being hinged along its top horizontal edge to said body portion, said auxiliary grating having a pair of latching arms pivotally secured at opposite sides of such auxiliary grating and slidably projecting through said main grating and provided with notches at their inner 95 ends for engagement with the main grating, said latches being adapted to normally hang downwardly within said main grating when said auxiliary grating is rocked downwardly into contact with said main grating. 100

2. A register comprising a body portion having a main grating, an auxiliary grating duplicating the main grating and adapted to normally lie parallel with and upon the main

grating, said auxiliary grating being hinged along its top horizontal edge to the body portion, whereby the auxiliary grating may be moved to a horizontal plane, a pair of latching arms pivotally connected to opposite sides of the auxiliary grating and slidably projecting through the main grating and having notches at their inner ends for engagement with the main grating, said latches

being adapted to normally hang downwardly 10 within the main grating when the auxiliary grating is lying in its normal position.

In testimony that I claim the foregoing I have hereunto set my hand at Sheboygan Falls, in the county of Sheboygan and State 15 of Wisconsin.

HUGO M. VOWINKEL.
